UNITED STATES PATENT OFFICE.

LOUIS VICTOR CIRAC, OF FALLOON, NEVADA.

BEET HARVESTER.

Application filed April 30, 1921. Serial No. 465,878.

To all whom it may concern:

Be it known that I, LOUIS VICTOR CIRAC, a citizen of the United States, and resident of Fallon, county of Churchill, and State 5 of Nevada, have invented a new and useful Beet Harvester, of which the following is a specification.

The present invention relates to improvements in beet harvesters and its object is to 10 provide a beet harvester that will top the beets before lifting them out of the ground, has a vertically adjustable topper, a vertically adjustable frame, an adjustable width of track so that it may be adjusted to the 15 width of the rows, and that may at the same time be used in connection with cultivating tools, such as cultivators, weeders, shovel plows, etc.

I attain these objects by means of the 20 mechanism illustrated in the accompanying drawing, in which Figure 1 represents a side view of my harvester, Figure 2 a plan view of the same, Figure 3 a detail view of a topper forming part of my harvester, Figure 25 4 a detail view showing the attachment of a tool shank to a girder forming part of my device.

Referring to the drawing more particularly, it will be seen that the wheels (1), 30 being of the size of mowing machine wheels, are connected by the axle (2). A frame (3) is supported on said axle and consists of a plurality of angle irons (4) arranged to follow the outlines of a longitudinal, rather 35 flat, rectangular body. About midways of their lengths the sides of the frame carry two vertical channel irons (6), their webs (7) lying flat against the angle irons which form the frame, their legs (8) inclined toward each other as shown in Figure 2. The 40 webs are provided with vertical slots (9) adapted to receive the sleeves (11). The latter fit on the axle and are provided with flanges (12) adapted to vertically slide in 45 the channels (6). They are reciprocated in said slots by means of two semi-circular links (14) one end of which pivots on the pin (16) extending from each channel, while the other end is pivotally connected 50 to a pair of links (17). The latter are suspended from arms (18) of the horizontal shaft (19) mounted in bearings formed in longitudinal plates (21). The latter are 55 supported on two transverse channel irons (22) and (23), which again are part of two complete transverse girders (24) and (26),

surrounding the whole frame. A third girder (27) is provided in front of said two girders.

The horizontal shaft (19) is provided 60 with a long lever arm (28), adapted to be handled by the driver. It will be seen from the drawing that by working the long lever arm the loose ends of the semicircular links (14) may be vertically reciprocated and 65 thereby adjust the height of the frame relative to the axle and the wheels. A seat (29), resting on the spring (31), is supported on the rear part of the frame and may be longitudinally adjusted so that 70 ordinarily the weight of the driver will about counterbalance the somewhat heavier weight of the front part of the machine and of the pole and double trees.

The girder (27) supports the topper (36), 75 which is intended to top the beets while they are still in the ground by means of a horizontally revolving disk (37). The latter forms the lower end of the vertical shaft (38) of circular cross-section, which is 80 joined to the vertical shaft (39) of rectangular cross-section by means of the socket (41) at the lower end of the rectangular shaft engaging the ball (42) at the upper end of the cylindrical shaft. Both shafts 85 are supported in the girder (27), the upper one in the upper channel and the lower one in the lower channel, extra-heavy pieces of iron (43) riveted to the channels increasing 90 the bearing surfaces of said channels. 90

The upper shaft is vertically adjustable and may be raised and lowered by means of the spring (40) positioned on the shaft between the upper channel and a collar (45) above said channel in combination with the 95 eccentric semi-circular disk (44) engaging the slot (46) at the upper end of the shaft. The disk is worked by a foot lever (47) which may be adjusted in different positions by means of the set comb (48). The lower 100 shaft receives rotary motion from the sprocket wheel (51) secured to one of the wheels (1) and consisting of two parts so that it may be taken off without removing the wheel. This sprocket wheel drives 105 another smaller sprocket wheel (52) at the end of a shaft (53) supported in a bearing (54) in a casting (56) mounted on the lower channel. The latter shaft carries at its other end a bevel gear (57) adapted to engage 110 another bevel gear (58) keyed to the vertical shaft (38). A longitudinal key way (61) is

provided in said vertical shaft, which allows of vertical motion of the shaft without vertically affecting the bevel gear (58). To hold both bevel gears in mesh, I provide a ring (62) above gear (58), which ring is secured to the lower channel by means of the metal bar (63). Thus it will be seen that when the harvester is in motion the disk will rotate and its height above the surface of the soil can be controlled by the driver by means of the foot lever (47). Between the lower channel and the disk a rotating rake (64) is provided adapted to throw the tops of the beets aside after they have been cut.

15 Each of the girders referred to is provided with a plurality of vertically aligned holes (66) adapted to receive the vertical shank (67) of any tool that it may be desired to use in connection with the machine. As will be seen from the drawing, the tool shank is provided with two recesses, corresponding in distance to the holes in the upper and lower girders. Each of the recesses is adapted to engage one of the holes and to slip over one edge forming the hole. It is forced over said edge and held in that position by means of the clamp (68) bracing against one of the legs of the channel and drawn toward the same by means of the screw (69) penetrating a slot (71) in said leg and an opposite hole (72) in the arched part of the clamp, a hexagonal nut (73) securing said clamp in its place.

35 The lower end of the shank is provided with a corrugated disk (76) to which a correspondingly equipped tool may be attached at any desired angle.

40 The lifting tool (77) shown in the drawing comprises two members fastened to the lower ends of two shanks secured to the rear girder in the manner described. They are further braced by two struts (78) connecting

a central part of said shanks to the central girder.

45 The wheels (1) are movable on the axle (2) so that the distance of the wheels from each other may be adjusted to suit the width of the rows of beets. For this purpose I provide a plurality of holes (81) in each end of the axle, through which pins may be inserted adapted to secure the wheels to the axle, while a collar (83) adapted to be secured to the axle by means of set screws (84) abuts against the inside of the hub.

55

I claim:

1. In a beet harvester of the character described a topping device comprising a vertical shaft consisting of an upper part and a lower part, a ball and socket joint between said two parts, cutting means at the lower end of the lower part, a bevel gear slidable on said lower part adapted to transmit rotary motion to the same, whereby it is rendered active, a slot in the upper end of the upper part, an eccentric engaging said slot adapted to impart downward motion to said shaft and spring means for opposing said downward motion.

60 2. In a beet harvester of the character described a topping device comprising a vertical shaft consisting of an upper part and a lower part, a ball and socket joint between said two parts, cutting means at the lower end of the lower part, a bevel gear slidable on said lower part adapted to transmit rotary motion to the same whereby it is rendered active, a slot in the upper end of the upper part, an eccentric engaging said slot adapted to impart downward motion to said shaft, 65 spring means for opposing said downward motion and means for brushing aside the tops of the beets mounted on said lower shaft.

70 80 LOUIS VICTOR CIRAC.
